FIG. 4.

INVENTOR:

Charles D. Rogers.
By Geo. H. Remington
atty.

UNITED STATES PATENT OFFICE.

CHARLES D. ROGERS, OF PROVIDENCE, RHODE ISLAND.

TIME-CHECK REGISTER.

SPECIFICATION forming part of Letters Patent No. 308,993, dated December 9, 1884.

Application filed April 2, 1884. (No model.)

To all whom it may concern:

Be it known that I, CHARLES D. ROGERS, a citizen of the United States, residing at Providence, in the county of Providence and State 5 of Rhode Island, have invented certain new and useful Improvements in Time-Check Registers; and I do hereby declare the following to be a full, clear, and exact description of the invention, such as will enable others skilled in 10 the art to which it appertains to make and use the same, reference being had to the accompanying drawings, and to letters or figures of reference marked thereon, which form a part of this specification.

15 This invention relates to time-check registers to be used in manufactories, &c.; and it consists, essentially, of a series of radially-arranged drawers or check-boxes adapted to be connected with clock-work or other suitable 20 mechanism, for the purpose of revolving the boxes successively beneath one or more stationary check conductors or chutes.

25 The invention further consists of two check receivers or chambers, each provided with a mouth opening into the chamber, the said openings being of unequal size.

The invention also consists of two classes or series of non-interchangeable time-checks, adapted to be deposited within said receiver.

30 The invention finally consists in arranging and connecting together a number of said receivers in a manufactory, whereby a workman, being upon any floor of the building, may deposit his time-check into the receiver, from whence it falls into a revolving box of the 35 register below, all as will be more fully hereinafter set forth.

The object of this invention is to enable a 40 workman to deposit his "in" or "out" check within a corresponding aperture of the stationary double receiver which leads to the revolving receptacles or numbered boxes below. By means of this device the person in charge thereof can readily compute the working time 45 of the operative whose checks are found therein.

In the annexed sheet of drawings, Figure 1 represents the improved system by which the checks are conveyed from any floor of a building 50 to the register below; Fig. 2, a vertical central section through the register, showing

mechanism for revolving the check-boxes; Fig. 3, a plan view of the same, a portion of the top being broken away. Fig. 4 is a front view of the double-check receiver; Fig. 5, a 55 top view of the same; Fig. 6, a vertical section through *o o* of Fig. 4, and Fig. 7 represents perspective views of the "out" and "in" checks adapted to be used herewith.

This invention (which is an improvement 60 upon the patent granted to Phillips and Griswold, August 22, 1882, No. 262,979) may be described as follows:

A in the drawings represents the casing of the apparatus or register provided with a central spindle, *a*. A crown-wheel, *b*, is secured to said spindle, the latter also carrying the circular box-holder *B*, provided with a series of radially-arranged and numbered boxes or pockets, *B'*. Said holder is adapted to rest 70 upon the wheel *b*, and is detachably secured thereto by means of the sliding key *c*. An extension, *D*, of the casing *A* is adapted to contain the clock-train *G*, or other suitable actuating mechanism, which engages with the 75 crown-wheel *b* by means of the pinion *c*. It is now evident that the action of the train *G* will cause the wheel *b* and holder *B* to revolve, thus carrying the boxes *B'* successively under the stationary pipes or chutes *f*. The cover 80 *a'* is hinged or otherwise adapted to render the boxes *B'* accessible. By means of electrical or other suitably-arranged escapement the boxes may be given an intermittent rotary motion.

85 The second portion, *E*, of this invention consists of two check receivers or chambers, *F F'*, of peculiar construction, connected by ties *t t*, and adapted to be secured to a wall or partition, as shown. About midway of each receiver is formed a mouth, *s*, opening into the chamber at *H*, (see Fig. 6,) said openings being of unequal size. The chambers *F F'* are adapted to connect with tubes *f*, as shown, and are lettered "out" and "in" respectively. 90

95 *H*, Fig. 7, represents the out-check, which is thinner but of greater diameter than the in-check *H'*, which latter is adapted to pass through the opening *H*, Fig. 6, and into the chamber *F'*.

100 It is obvious that various forms of checks may be substituted for the flat ones shown—

such, for instance, as spherical, rectangular, &c.—but in any case the out-check cannot enter the in-chamber F' nor the in-check enter the out-chamber F. I do not, however, limit myself to this exact form and construction, as the receivers may be modified considerably without departing from the spirit of the invention.

In Fig. 1 I have represented a building provided with a series of check-receivers, E, connected by tubes f, terminating below in the register A, before described.

In a large number of industrial establishments it is the present custom to issue daily to the operatives what are termed "time-checks," each bearing a number or character. These checks are collected during the day by one or more persons, whose duty it is to keep the time of each employé.

By means of this invention much labor is saved, thus enabling a child even to readily and accurately make up the time for several hundred operatives.

To illustrate the operation, we will assume that the time is to be kept in half-hours, the check-boxes B' being numbered correspondingly. The stationary tubes or conductors f are located over said boxes, the in-tube being one box or a half-hour ahead of the out-tube, all as shown in Fig. 3, when, now, No. 1 workman, upon entering the room just prior to the hour of seven, (to commence work,) will drop an in-check, H', into the receiver F', from whence it falls into the box numbered 7. At the stroke of seven o'clock, however, the box-holder B revolves one box, or a half-hour ahead. Suppose, now, another workman (No. 2) arrives late, or just after seven o'clock, he also deposits a check, H', into the receiver F', which falls into the box 7½. If both men work until twelve o'clock, upon leaving the room they each will deposit an out-check, H, into the receiver F, from whence they both fall into the box numbered 12. Should the time-keeper now collect the checks it will be found that No. 1 workman commenced work at seven o'clock and ceased at twelve o'clock, and he is credited with five hours. No. 2's checks indicate that he commenced work at half-past seven o'clock and left at twelve o'clock, consequently he is credited with only four and one-half hours labor.

The in-checks in all cases with this inven-

tion are found in the box indicating the actual hour when the operative commenced work, and the out-checks will be found in the box indicating the hour when he ceased work. This result is obtained by means of the system of double checks and receivers, the in-receiver being invariably ahead of the out-receiver when used with the revolving boxes.

As previously stated, the clock-work G, or other escapement mechanism of the register A, may be connected electrically with a central or other standard time provided with pins, &c., adapted to operate the holder B every hour or fraction thereof, as may be desired.

Having thus described my invention, what I claim, and desire to secure by Letters Patent, is—

1. In a time-check register, the holder herein described adapted to carry a series of check-boxes, and provided with means for rotating said holder, and further provided with locking means, whereby it is detachably secured to the actuating-spindle, substantially as shown and set forth.

2. In a time-check register, the combination, with a series of check-boxes adapted to receive rotary motion, of two stationary tubes or conductors arranged side by side over said boxes, and adapted to transmit checks into two adjacent boxes, substantially as shown, and for the purpose set forth.

3. The time-check register herein described, consisting of the hinged casing A, provided with the spindle a, carrying the wheel b, and box-holder B, in combination with the clock-train G and stationary check-conductors f f, all combined and arranged substantially as shown, and for the purpose set forth.

4. The combination, with the double-check receiver E, provided with unequal openings H', and means for distinguishing the same, of a time-check register provided with a series of radially-arranged and numbered check-boxes adapted to receive rotary motion by suitable means, substantially as shown and set forth.

In testimony whereof I have affixed my signature in presence of two witnesses.

CHARLES D. ROGERS.
